UNITED STATES PATENT OFFICE.

JOHANNES CLETON, JR., OF ROTTERDAM, NETHERLANDS.

GLASS GRINDING AND POLISHING MACHINE.

Application filed May 16, 1927, Serial No. 191,869, and in the Netherlands October 16, 1924.

This invention relates to a machine for simultaneously grinding or polishing a number of grooves located adjacent each other, in plates of glass, marble and like materials.

Plates of this kind are used for instance in meat slicing machines; the grooves extend from one of the edges of the plate over a part of its length and prevent the meat to be sliced slipping under the pressure of the knife during the cutting movement.

Up to the present the grooves were generally made by hand and one after the other. The plate to be ground was pressed against a rotating grinding disc and reciprocated until the desired depth of the groove was obtained.

It will be clear that this method is very uneconomical and inefficient for making a great number of grooves, especially because it is necessary that they have all exactly the same depth so that a sufficiently sharp edge remains between two adjacent grooves.

The object of the present invention is to provide a machine for automatically grinding such plates. The machine has a plurality of grinding discs arranged upon a rotatable shaft, a supporting table for the plate to be worked, arranged below the disc shaft in a plane parallel to the disk shaft and adjustable in vertical direction, and a driving mechanism adapted to impart a reciprocating motion to the table in a horizontal plane along the discs and constructed in such a way that during the working stroke the desired rate of feed is obtained, but a greater speed during the retrogressive movement.

Machines having a rotating shaft with a plurality of grinding discs fixed thereto are known in themselves. In the known machines of this kind the piece of work may also be fixed upon a horizontally moving table. These machines are used for providing glass plates with bevelled edges, or for grinding profiles into marble blocks. However for the purpose as described above these known machines cannot efficiently be used.

In grinding fine grooves positioned closely to one another, one has to regulate the feeding speed in such a manner that the discs with the carborundum powder supplied thereto do not shatter or otherwise remove the edges between the grooves.

Preferably metal discs are used, as it is found in practice that these discs, with addition of water and carborundum powder

have a larger capacity than carborundum discs. The latter have the drawback that the feeding speed cannot be increased without shattering or removing the edges between the grooves.

According to the invention the driving mechanism of the table may comprise a horizontal disc, rotated about a vertical axis and provided with a curved cam track co-operating with a pin projecting from the table.

In the accompanying drawings a machine according to the invention is illustrated by way of example.

Fig. 1 is a front elevation of the machine,
Fig. 2 is an end elevation of the same,

Fig. 3 is a detail on larger scale,

Figs. 4 and 5 are a front elevation and a plan view respectively of a glass plate with grooves.

The table 1 is mounted in the frame 2 movable in a horizontal plane. The frame 2 itself may be adjusted in a vertical direction by means of a threaded rod 3, bevel gear 4 and a handwheel 5. The table 1, supporting the plate to be ground, is driven from the shaft 6. Upon said shaft is first fixed the driving pulley 7, secondly a pinion 8 meshing with a gear wheel 9. To the shaft of said gearwheel 9 is attached a pulley 10, driving by means of the pulley 11 a wormshaft 12. The worm 13 upon said shaft is meshing with a worm-wheel 14, on the shaft of which is fixed a disc 15, provided with a curved groove or track 16. In this track fits a pin 17, fixed to the table 1. In this way the rotating movement of the worm-wheel 14 is transformed into a reciprocating movement of the table. The curved path 16 is chosen in such a way that a slow feeding movement and an accelerated return movement is obtained.

This construction has the advantage, that by varying the form of the track 16 one may adjust the speed of the table both at the forward stroke and the return stroke, also the pin, clearing the bottom of the groove as shown in Fig. 1, and bearing only against the propelling sides of the groove, is freed from vertical vibrations arising in the disk 15 from the movements of its driving mechanism, and which would otherwise be communicated through the pin to the table, jarring the latter so as to cause damage to the edges being ground between the grooves.

Above the table and parallel with it, is

mounted the shaft 18, supported in its bearings 19 and driven by the pulley 20. Upon this shaft the grinding discs 21 are mounted.

If the grooves are to be ground as illustrated in Figures 4 and 5 of the drawings the discs have the profile 22. The depth of the grooves may be adjusted by means of the handwheel 5, in lowering or raising the supporting table 1. The depth may be measured 10 in supplying marks upon the handwheel 5, so that a certain angle of rotation corresponds with a certain displacement of the table.

In moving the table up and down the wormshaft 12 also moves, whereas the shaft 15 of the gearwheel 9 and pulley 10 is stationary. It will be advisable for this reason to provide the belt over the pulleys 10 and 11 with a device for keeping the belt stretched.

The machine may be also employed to 20 polish by means of discs of stone, leather or felt.

I claim:

A machine for grinding parallel grooves partway across a plate, and preserving accurately straight and keen edges between the 25 grooves and surface of the plate, comprising a horizontal shaft with parallel vertical grinding disks mounted to rotate therewith, a horizontal table arranged below and having a travel in a plane tangent to said disks, 30 means for adjusting said table vertically toward and from said disks, guiding means for said table accurately preserving its plane of travel and its lines of movement parallel with said disks, means for reciprocating said table comprising a rotatable horizontal cam groove designed to slowly advance the table toward the disks and rapidly return the same, and a projection from the table engaging only the propelling walls of said groove, 40 to avoid as far as possible the vibration of the table by its reciprocating means.

In testimony whereof I affix my signature.

JOHANNES CLETON, JR.
